United States Patent Office.

JOHN NICHOLS, OF BATTLE CREEK, MICHIGAN.

Letters Patent No. 91,658, dated June 22, 1869.

IMPROVEMENT IN THRESHING-MACHINE CONCAVE.

The Schedule referred to in these Letters Patent and making part of the same.

To all whom it may concern:

Be it known that I, JOHN NICHOLS, of Battle Creek, county of Calhoun, and State of Michigan, have invented a new and useful Improvement in Threshing-Machine Concaves, of which the following is a full, clear, and exact description, reference being had to the accompanying drawings, making a part of this specification, in which—

Figure 1 is a plan or top view of the concave.

Figure 2 is a vertical section through the same, in line $x x$, fig. 1.

Similar letters of reference denote corresponding parts wherever used.

It is a fact well understood by those familiar with the working of threshing-machines, that owing to the difference of kinds and conditions of grain required to be operated upon, a machine which operates well and efficiently upon a certain kind, or a certain condition of different kinds of grain, is very defective in its operation when employed for threshing a different kind of grain or the same kind of grain under a different condition.

For example, where the grain is in good condition, well cured, and the straw is straight, the grain may be readily fed to, and will be effectively operated upon, by most of the various machines in use; but it frequently happens, where the grain is tangled, that it is a difficult task to feed it properly to the machine, and, as a consequence, the grain being presented in tangled masses or bundles, the machine becomes choked, and the operation is suspended until the cylinder can be cleared.

Again, where the grain is thoroughly dry, the machine may work with ease, but where it is wet or tough, it has frequently been found almost impossible to make the machine operate upon it at all satisfactorily.

My invention has for its object the remedying of these difficulties and defects; and relates to a novel construction and arrangement of parts, whereby the machine may be readily adapted to the kind or condition of grain to be operated upon; to this end,

The invention consists in making the concave in removable sections, one of which is made blank, and adapted to be transferred from a position in front to one intermediate between, or behind the toothed sections, as the conditions of the grain may require. If it is preferred, the two sections may be made in one piece, and the desired change in the adaptation of the machine made by reversing the position of the section thus formed, or any other arrangement may be introduced which will accomplish the same object.

In the accompanying drawings—

A represents a frame, of any usual or suitable construction, in cross-pieces $a a$, in the upper part of

which is mounted the concave, composed of grooved or flanged supporting-sides B, adapted to receive and to support the toothed and perforated concave bed B', which, in this instance, is composed of removable blank section b and toothed sections $b^1 b^1$, a stationary blank section, b^2 , and removable apron or bed-board b^3 .

These sections may be of any desired number consistent with the required strength, and the concave, as a whole, may conform in its construction to those in ordinary use.

The grooves in the side plates B are curved, and made to conform to or nearly to the arc of a circle, of which the axis of the cylinder (not shown in drawing) is the centre, and the sections $b^1 b^1$, conforming in shape thereto, slide into said grooves, and may be readily removed, and their relative position changed, as the condition of the grain may require.

The removable apron b^3 also fits in grooves in the front of the sides B, and is removed when it is desired to change the sections.

When in position, the several sections are sustained against the action of the cylinder by stationary sections b^2 .

The grooved or flanged sides B have pivotal supports, at b^1 , in the main frame, upon which, as a centre, the concave may be adjusted or vibrated, to bring it nearer or to move it away from the cylinder. This adjustment is effected by any of the devices usually employed for that purpose.

Parts of the machine not particularly mentioned in the foregoing description may be constructed and arranged in any usual or desired manner.

From the description given of the sectional concave, it will be seen that where the straw is straight and in good condition, and where the feeding and threshing of the grain is easily effected, the blank section b may be placed next to the stationary section b^2 ; then, by the adjustment of the forward or apron-end of the concave, the teeth of the concave and threshing-cylinder may be made to interlock to a greater or less extent, and thereby to act with the required force upon the grain, while all unnecessary injury to the straw may be avoided.

Where the grain is tough or wet, it is sometimes found desirable to give the teeth an intermediate space, in which to clear themselves, and thereby prevent the clogging of the machine. In this case the blank sections should be placed between the toothed sections.

Where the grain is tangled and difficult to feed, the blank section should be placed next to the feed-board or apron b^3 , so as to form a curved extension thereof, conforming to the direction of movement of the teeth of the cylinder, and said teeth are thereby enabled

to seize and carry forward the grain to the point of threshing, thereby assisting in the operation of feeding.

The operation of the other parts of the machine will be understood without further description.

What I claim as new, and desire to secure by Letters Patent, is—

1. A concave, composed of removable sections, for the purpose set forth.

2. The removable blank section of the concave, adapted to be transposed relative to the toothed

sections, supported at their ends in grooved or flanged side pieces, substantially as and for the purpose set forth.

3. A concave, composed of the removable sections, adapted to be transposed, as set forth, in combination with a removable apron.

JOHN NICHOLS.
